US00D611017S

(12) **United States Design Patent**
Loh et al.

(10) **Patent No.:** **US D611,017 S**
(45) **Date of Patent:** **** Mar. 2, 2010**

(54) **COMMUNICATION DEVICE HOUSING**

(75) Inventors: **Dianne Loh**, Singapore (SG); **Bee Lay Khoo**, Singapore (SG); **Ee Fong Lee**, Singapore (SG)

(73) Assignee: **Motorola, Inc.**, Schaumburg, IL (US)

(**) Term: **14 Years**

(21) Appl. No.: **29/299,920**

(22) Filed: **Jan. 7, 2008**

(51) **LOC (9) Cl.** **14-03**

(57) **CLAIM**

The ornamental design for a communication device housing, as shown and described.

DESCRIPTION

FIG. 1 is a perspective view of an ornamental design for a communication device housing.

FIG. 2 is a front view thereof.

FIG. 3 is a rear view thereof.

FIG. 4 is a first side view thereof.

FIG. 5 is a second side view thereof.

FIG. 6 is a top view thereof; and,

FIG. 7 is a bottom view thereof.

The broken lines that show the outermost periphery of non-claimed features represent boundaries of the claimed design. All other broken lines are directed to environment. The broken lines and unshaded regions that are defined by broken lines form no part of the claimed design.

1 Claim, 4 Drawing Sheets
